UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

SLIP-DRUM HOIST.

Application filed September 10, 1923. Serial No. 661,949.

To all whom it may concern:

Be it known that I, CHARLES C. HANSEN, a citizen of the United States, and a resident of Easton, county of Northampton, and 5 State of Pennsylvania, have invented a certain Slip-Drum Hoist, of which the following is a specification, accompanied by drawings.

This invention relates to hoists, but more 10 particularly to a power driven hoist of the double drum type, in which either drum may be driven from a common crank shaft.

The objects of the invention are to enable 15 two drums, as for instance, a haulage drum and a tail rope drum to be driven from a common source by improved means and devices which are substantially unaffected by gravity or centrifugal force for automatically disconnecting one drum, and connecting 20 the other drum to the driving shaft in accordance with the direction of rotation of the shaft.

A further object of the invention is to produce 25 a pawl mechanism for a double drum hoist, which is positively operated and reliable in its action.

Further objects of the invention will hereinafter appear, and the invention is shown 30 in one of its preferred forms in the drawings, in which—

Figure 1 is a side elevation of the hoist,

Figure 2 is a longitudinal sectional elevation 35 on the line 2—2 of Figure 4, looking in the direction of the arrows,

Figure 3 is a transverse sectional elevation 40 on the line 3—3 of Figure 2, looking in the direction of the arrows,

Figure 4 is a view similar to Figure 3 with the pawls in a different position,

Figure 5 is an enlarged detail perspective 45 view of the pawls, and

Figure 6 is an enlarged detail perspective 50 view of one pawl, showing the method of assembly.

Referring to the drawings, the base plate A on which the hoist is mounted, is provided with a clamping member preferably in the form of a saddle clamp B having the clamping bolts C for securing the hoist to a column, cross bar or support. Any suitable motor may be provided for the hoist and in this instance, a fluid pressure motor is indicated, having the motor casing D mounted on the frame E bolted to the base plate, as by means of the bolts F. A cylin-

der head G is secured to the cylinder by the cap bolts H and fluid pressure, as for instance compressed air, is supplied through the inlet J controlled by a suitable valve K in the valve chest L, and manipulated by the valve lever O. In this instance, the motor is assumed to be a reversible motor, the reversal of which is controlled by the valve lever O. An oiling device P of any suitable type, may be applied to the motor.

A center bearing Q shown in this instance in the form of a shell, having a tubular body and a flanged portion R is connected to the motor cylinder D and the cylinder head G by means of the cap bolts H. The opposite end of the center bearing is supported in the gear box S, which is secured to the frame A, as by the bolts T. A center bearing retaining screw U suitably secures the center bearing to the inner wall V of the gear box S. An oiling connection W may be provided upon the gear box. The gear box cover X is secured to the gear box by means of the bolts Y. The construction of the motor and frame so far described, forms a simple and compact frame for the hoist, easily assembled and dis-assembled and permitting ready accessibility to the operative parts of the hoist.

A main driving shaft a passing centrally through the center bearing Q is supported in the ball bearings b and c and is connected to be rotated by the motor. The driving shaft a is provided with the crank disc d having the crank pin e connected to the piston f of the motor by means of the ball bearing g, so that the driving shaft a operates throughout in ball bearings. A driving pinion h is keyed to the driving shaft a and a retaining washer j is held against the driving pinion by means of the pin k. The driving pinion h meshes with an intermediate gear o, keyed to the counter shaft p operating in the ball bearings q and r mounted in the gear box S. An intermediate pinion s on the counter shaft p, meshes with the internal gear t of the main driver u adapted to rotate on the center bearing Q, from which power is taken for driving either one of the two drums.

The haulage drum v to which one length of the rope w is adapted to be connected, rotates upon the center bearing Q and the concentric tail rope drum x to which the tail rope y is connected, preferably rotates

upon the haulage drum v , as indicated particularly in Figure 2. Such construction of the drums materially reduces the over-all length of the hoist and produces a more 5 compact and better balanced hoist than heretofore.

Means are provided for automatically connecting the main driver u to one or the other of the drums v and x in accordance with the 10 direction of rotation of the driving shaft a , and for this purpose, the haulage drum v is provided with a driver z preferably in the form of a plate having clutch members in the form of teeth 2 on its face, having 15 cam surfaces 3. The driver z is suitably secured to the haulage drum by means of the bolts 4 and for convenience of description, may be termed the "inner driver".

The tail rope drum x is likewise provided 20 with a driver 5 opposed to the driver z , and preferably in the form of a plate, having clutch members on its face in the form of teeth 6, facing in the opposite direction from the teeth 2, on the driver z , and having cam 25 surfaces 7. The driver 5 is secured to the tail rope drum x by means of the bolts 8 and for convenience of description, may be termed the "outer driver". The terms 30 "inner" and "outer" as applied to the opposed drivers z and 5 carried by the drums respectively, are not to be understood as necessarily limited to ratchet rings concentric with the axis of the rotation of the machine, but are intended to be used as suitable 35 designations for two opposed ratchet faces for the drums, having reference to some fixed point of the machine, which obviously need not be the driving shaft.

The main driver u is provided with a 40 clutch mechanism preferably in the form of a pair of separate removable pawls 9 and 10 pivoted on different centers and carried respectively by the sectors 11 and 12, each of which is formed with engaging devices 45 preferably in the form of gear teeth 13 for a portion of its periphery. The sectors 11 and 12 are formed with extensions 14 which are adapted to fit into the recesses 15 in the lugs 16 formed on the main driver u . The pawls 9 and 10 are so constructed and 50 arranged that the pawl 9 may be rocked in one direction into engagement with the inner driver z or the pawl 10 may be rocked in the opposite direction as the pawl 9 into engagement with the outer driver 5, in accordance 55 with the direction of rotation of the driving shaft a , and when one pawl is rocked into engagement with one driver, the other pawl is simultaneously rocked but in 60 the opposite direction to inoperative position out of engagement with the other driver.

In the operation of the hoist, if it be assumed that the driving shaft a is rotated in the direction of the arrow 17 in Figure 3, the 65 main driver u will be rotated by the train of

gearing described, in the opposite direction, and the pawl 10 will have been rocked by the pawl 9 riding over one of the cam surfaces 3 on the inner driver z into engagement with one of the teeth 6 of the outer driver 70 5, thus driving the tail rope drum x in the same direction as the main driver, but in the opposite direction to the rotation of the driving shaft a . The arrow 18 in Figure 1 on the tail rope drum x , indicates the direction 75 of rotation of the said drum, under such circumstances, when power is applied to the drum to wind up the tail rope. The haulage drum v is disconnected from the driving shaft a , which is freely rotated in the same 80 direction as the tail rope drum x , as the rope is un-wound from said haulage drum.

Upon reversing the direction of rotation of the driving shaft a , as indicated in Figure 4, and causing it to rotate in the 85 direction of the arrow 17^a, the direction of rotation of the main driver u will be reversed and the pawl 10 will be actuated by one of the cam surfaces 7 on the outer driver 5 so as to bring the pawl 9 into engagement 90 with one of the teeth 2 on the inner driver z , thus driving the haulage drum v in the direction of the arrow 19 in Figure 1, oppositely to the direction of rotation of the driving shaft. In such case, the rope will be wound 95 up on the haulage drum and the tail rope drum will be rotated freely in the direction of the haulage drum, as the rope is unwound from the tail rope drum. One drum or the other will be automatically connected to be 100 driven from the driver, as often as the direction of rotation of the driving shaft is reversed.

In a hoist of the character described, a 105 brake is preferably provided for one of the drums, and it is unnecessary to provide a brake for both drums in accordance with my construction. In this instance, the tail rope drum x may be conveniently provided with a flange 20 to which a brake band 21 having 110 a suitable lining 22, is applied. A brake lever 23 is connected in any suitable manner to the rod 24 having oppositely threaded portions 25 on which are mounted internally threaded nuts 26 and 27. By actuating the 115 lever 23 in one direction, the brake band 21, which is connected at its ends to the lugs 28 and 29, carried by the nuts 26 and 27 respectively, will be tightened about the tail rope drum x , and controls the rotation 120 of both drums, as long as the drums are connected by the agency of the cable and are doing work.

I claim:

1. In a hoist, the combination of a frame, 125 a driving shaft, two drums rotatable about the driving shaft, a motor connected to operate the driving shaft, opposed drivers carried by said drums, and a pair of pawls having engaging devices so connected that 130

when one pawl rocks in one direction and automatically connects one drum to the driving shaft, the other pawl is rocked in the opposite direction and assumes an inoperative position.

2. In a hoist, the combination of a frame, a driving shaft, two drums rotatable relatively to the driving shaft, a motor connected to operate said driving shaft, a main driver, opposed drivers carried by said drums, and a pair of pawls carried by the main driver and geared together, whereby one pawl automatically connects one drum driver to the main driver, while the other pawl is in inoperative position.

3. In a hoist, the combination of a frame, a driving shaft, two drums rotatable relatively to the driving shaft, a motor connected to operate said driving shaft, a main driver, opposed drivers carried by said drums, and a clutch mechanism for automatically disconnecting one drum driver and connecting the other drum driver to the main driver in accordance with the direction of rotation of the driving shaft, said mechanism comprising a pair of toothed sectors and pawls carried by said sectors.

In testimony whereof I have signed this specification.

CHARLES C. HANSEN.
